UNITED STATES PATENT OFFICE.

ELIJAH A. WILCOX, OF NEW YORK, N. Y.

DESIGN FOR A PILLOW-TOP.

SPECIFICATION forming part of Design No. 34,229, dated March 12, 1901.

Application filed January 24, 1901. Serial No. 44,633. Term of patent 7 years.

To all whom it may concern:

Be it known that I, ELIJAH A. WILCOX, a citizen of the United States, residing at 69 Leonard street, New York city, in the county of New York, State of New York, have invented and produced a new and original Design for a Pillow-Top; and I do declare the following to be a full, clear, and exact description of the same, reference being had to the accompanying drawing, forming part thereof.

My novel design for a pillow-top has for its leading feature, and consists in, the representation of a monogram formed of a series of interwoven lines, as shown in the accompanying drawing.

What I claim is—

The design for a pillow-top as herein shown and described.

In testimony whereof I affix my signature in the presence of two witnesses.

ELIJAH A. WILCOX.
